FREE PISTON COMPRESSOR AND CONTROL
THEREFOR

George A. Mueller, Jr., Hamilton, Ohio, assignor,
by mesne assignments, to Lima-Hamilton Corporation,
Hamilton, Ohio, a corporation of
Virginia

Application May 16, 1947, Serial No. 748,591

12 Claims. (Cl. 123—46)

1 This invention relates to free piston internal combustion engines and is particularly directed to a combined engine-compressor unit and a control therefor.

The primary object of the invention is to provide a free-piston engine-compressor and a control therefor which results in the extent of the stroke of the power and compressor pistons remaining substantially constant over the operating range.

Another object of the invention is to provide a control for a free-piston engine-compressor unit in which simple hydraulic or similar relays are operated by an engine part at the ends of a stroke of predetermined length, the relays in turn controlling the amount of energy imparted to the cycle at each end of the stroke of the pistons.

Still another object of the invention is to provide a device of the above character in which the load on the engine parts added by the control elements is minimized and which is inexpensive to construct and maintain.

Other objects and advantages of the invention will become apparent from the following specification, reference being had to the accompanying drawings in which:

Figure 1 is a diagrammatic side elevation of a free piston engine-compressor unit with parts broken away to show the relative positions occupied by the several control elements; Fig. 2 is diagrammatic view, partly in section, of the unit showing the pistons and their synchronizing devices from which certain control elements may be conveniently operated; and Fig. 3 is a composite, diagrammatic sectional view of the several control elements.

Referring to the drawings, and particularly to Figs. 1 and 2, the present invention is shown applied to a free piston compressor unit of the opposed piston type. At the ends of the unit are headers 2 and 4 which communicate with a common compressed air trunk 5 and, thereby, with a receiver 6, an inwardly opening check valve 8 being disposed at the entrance to the receiver.

Each of the opposed pistons comprises a power piston 10, of appropriate diameter, then a stem or crosshead portion 12 to which is connected a compressor piston 14 and finally a bounce piston 16. Cylinders of the proper diameter are associated with each of the piston sections and in Fig. 2 the power cylinder is designated 20, the forward compressing chamber or cylinder is designated 22, the compressor cylinder 24 and the bounce cylinder 26.

The pistons are synchronized in their move-

ments by racks 28—29 which extend toward each other from connectors 30 on each crosshead 12. The racks are thus of short length and are so disposed that they do not pass between chambers containing air at different pressures. The necessity for packing glands around the racks is thus eliminated. The usual synchronizing pinion 32 meshes with both racks and reciprocates on a hub or shaft 34 extending from the center of the exterior of the power cylinder or at some other convenient location.

2 Air is drawn into the unit to be compressed for scavenging the engine cylinder as well as for use in the receiver 6. A common intake manifold 36 is provided which communicates with the atmosphere through appropriate filters (not shown) and with both ends of the cylinder in which compressor pistons 14 operates. This cylinder is, as above stated, divided into an inner part 22 in which scavenging air is compressed, and an outer part 24 in which air is compressed and fed to the receiver 6. The passage between the intake manifold and the scavenging air compressing cylinder is designated 38 and a plurality of similar, self contained check valves 40 control the passage of air from manifold to cylinder. At one side the check valves 40 open toward the cylinder to admit air on the intake stroke, and at the other side of the cylinder, valves 41 control the outward flow of air from the cylinder 22 to a scavenging air header 42 which communicates with the power cylinder 20 in the usual manner by piston controlled ports.

Air is drawn into the compressor cylinder through intake ports 44 and discharged through ports 46 to the header 2 on the rearward stroke of compressor piston 14. From the compressor headers the air passes check valve 8 and enters receiver 6 from which it may be utilized in any known manner.

Bounce cylinders 26 operate as chambers in which energy is stored during the outward stroke of the pistons to be utilized to cause return of the pistons to firing position. The major portion of the air in these chambers is preferably contained in annular side chambers 27, although a straight, continuous chamber may be used. The bounce chambers are closed spaces to which air is added or withdrawn as hereinafter described. It will be appreciated that the extent of the inward stroke of the pistons depends on the energy contained in the air in the bounce chambers and that this stroke may be lengthened or shortened by changing the quantity of air in the bounce chambers and its initial pressure.

The present invention provides a control system which is actuated by the pistons, working through the synchronizing racks and mechanism to be described, that controls the supply of fuel to the firing cylinder and the air in the bounce chambers in such a manner that the stroke of the pistons remains substantially constant throughout the working range.

A dump valve 50 is provided, either in the compressed air trunk 5 or in a by-pass conduit 51 leading from the trunk to a convenient location. Valve 50 may be operated by any suitable means such as a piston 52 working in a cylinder 53 against the tension of a spring 54. A pilot valve 55 operated by air from the receiver admits air at receiver pressure to the front face of piston 52 whenever the receiver pressure reaches a predetermined level which may be adjusted by varying the force of a spring 56 against which pilot valve 55 moves toward open position. Suitable air passages are provided in the valve body to admit and exhaust air to and from cylinder 53, the vent passage being designated 57 and the passage by which air enters from the receiver 58. These passages are, of course, opened and closed by the pilot valve 55. It will thus be apparent that when the receiver is charged with air at its intended pressure the dump valve is opened and the load on the compressor is reduced to only that required to maintain the pistons in operation, nearly all of the energy taken from the cycle on the outstroke of the pistons being stored in the air in the bounce chambers and returned to the cycle by expansion on the next succeeding instroke. During the period that the receiver is full of air at its intended pressure, check valve 8 functions to prevent this pressure from acting against the compressor and prevents the escape of air from the receiver.

Fuel control is accomplished by a device operating in response to the extent of the outstroke of the pistons. The engine fuel pump is shown diagrammatically at 60 and includes the usual adjusting rack 62 to which is connected a piston 64 operating in a cylinder 66 and biased to the "off" position by a spring 68. Pressure at the rear of the piston moves the rack in a direction such that more fuel is injected at each stroke of the fuel pump plunger. An adjustable needle valve 70 is inserted in the bleed passage from cylinder 66 so that the rate of response of the fuel control may be changed at the selection of the operator. The fuel pump may be operated in any suitable manner as by a cam 61 rocked by a rod 63.

Shaft 34 on which the synchronizing pinion is mounted is continued out from the side of the engine and carries a second pinion 72 which cooperates with an arcuate rack 74 formed on the end of a lever 76 pivoted at 78 and carrying adjustable actuating members 80, 81 at its short end. It will thus be seen that as pinion 72 rotates the actuating members 80 and 81 reciprocate about pivot point 78 with the extent of their reciprocation determined by the extent of the rotation of pinion 72. Rod 63 may be operated by lever 76 to move fuel cam 61.

Actuating member 81, in its reciprocation, abuts against a stem 82 of a piston type valve 83 the enlarged rear end of which operates in a dash pot cylinder 84, the valve being biased to open position by a spring 85. Valve 83 controls the flow of oil or other actuating fluid between a conduit 86 and a conduit 88. Conduit

86 is fed with oil under pressure by a pump 90 and conduit 88 communicates with cylinder 86 at the fuel pump. Thus, as valve 83 moves to such a position that its reduced area, designated 82, opens communication between conduits 86 and 88 a small quantity of oil will pass the valve and enter cylinder 86. While the valve remains closed cylinder 86 tends to drain into a bleed passage 94 around needle valve 70. In the normal operation of the engine the stroke is adjusted so that valve 83 opens periodically in an amount sufficient to move the fuel rack 62 to the proper adjusted position. If the engine stroke is too long at the outer end, valve 83 is closed by abutment of actuating member 81 against stem 82 and less fuel is injected at the next stroke since the supply of oil is cut off to cylinder 86 and the rack tends to drift toward the off position. The sensitivity of the device can be changed by adjustment of needle valve 70 so that persistent trends are followed rather than individual overstrokes.

To control the extent of the instroke of the pistons a valve 96 provided with an abutment 98 is provided to control the flow of oil between passages 100 and 101. Passage 100 communicates with pump 90 and passage 101 communicates with a bounce air governor 102. Valve 96 may be conveniently controlled by a spring 104 acting on its rear end and working in a dash-pot cylinder 105. The valve passage is designated 106 and, as in the case of valve 83, the unit is biased to open position and is moved to cut-off position by abutment of actuating element 98 against stem 96.

The bounce air governor 102 may take any suitable form by which air under pressure is admitted to or bled from the direct bounce chambers 26. A common passage 108 leads to these chambers 40 and enters the body of governor 102 in a common conduit 110. Air under pressure is supplied to the governor 102 by a conduit 112 which connects to an air storage bottle 114 having the usual shut-off valve 115 at its outlet. A vent pipe 116 is also connected in the governor body.

Governor 102 contains a slide valve 120 of the piston type urged in one direction by a spring 121 and in the opposite direction by oil under pressure entering from conduit 101 and acting against the face of the piston valve 120. Oil thus entering bleeds past an adjustable needle valve 122 to a drain passage 124 so that the rate of bleed, and thus the rate of actuation of the valve 120, may be easily controlled. It will be seen that in the position to which the valve 120 is urged, in the absence of pressure on its face, communication is opened between passage 110 which leads to the direct bounce cylinders and the vent passage 116 through an upper communicating passage 126 formed in the body 102. The pressure in the direct bounce chambers is thus reduced.

When oil under pressure enters through pipe 101 and acts on the face of valve 120 moving it against its spring, the vent passage 116 is closed and communication is opened between air line 112 and the charging bottle 114 and passage 110 to the direct bounce chambers thus increasing the pressure of air in these chambers. As the pressure of the air in the direct bounce chambers increases the extent of the instroke of the pistons is increased and, conversely the lower pressure in the direct bounce chambers permits a shorter instroke of the pistons to be made. The control thus results in valve 120 hunting between a position of charging and venting the direct bounce

chambers, with the rate of change being governed largely by the setting of needle valve 122. Persistent trends toward an increase or decrease in the length of stroke of the pistons will be followed where individual differences in the strokes do not necessarily result in a change in the pressure in the direct bounce chambers.

In operation the compressor works against a predetermined receiver pressure and so long as the dump valve in the receiver line remains closed the compressor is under load and sufficient fuel is injected to cause the pistons to compress air to a pressure high enough to overcome the check valve 8 in the compressed air header. When the dump valve 50 opens by reason of the desired receiver pressure being attained, the check valve 8 remains closed and the compressor idles at full stroke and just enough fuel is injected to maintain the proper stroke length. Should the compressor begin to understroke the fuel will be increased by reason of the movement of valve 83 to a position such that oil passes into conduit 88 and hence to cylinder 66 adjacent the fuel rack. Should the compressor then tend to overstroke the supply of oil to conduit 88 is cut off, the contents of cylinder 66 bled past valve 70 to line 94 and the rack 62 drifts toward cut-off position.

At the inner end of the stroke the proper piston position is maintained by increasing or decreasing the pressure in the direct bounce chambers. As the load on the compressor increases and the amount of fuel injected at each stroke is, therefore, increased the pressure on the direct bounce chambers tends to build up and thus forces the pistons closer together at the exact compression strokes. If this tendency goes objectionably far, actuating element 80 strikes the stem 98 of valve 96 which then operates to cut off communication between passages 100 and 101 so that fluid operating against the front face of piston valves 120 can bleed past needle valve 122 into the drain line 124. The valve 120 then drifts to the left under the influence of spring 121 and opens communication, through passage 126, between the direct bounce line 110 and the vent line 116. The direct bounce spaces are thus vented to a lower pressure and the pistons urged together less forcibly. The balance of operation is thus restored and succeeding end strokes of the pistons will be of the proper length. This venting continues until actuating element 80 no longer strikes stem 98 and communication to the oil pressure line 100 is again restored and valve 120 moved to a position such that the venting of the direct bounce chambers is stopped. Continued understroking causes valve 120 to move to charging position and the direct bounce chamber pressure is increased.

It will be seen that the present invention provides a control balance which is capable of precise adjustment so that the length of stroke of the pistons will remain substantially constant, varying between limits which can be easily determined and maintained.

While the invention has been described in connection with a particular form and disposition of the parts it should be appreciated that numerous modifications and changes may be made without departing from the spirit of the appended claims.

What I claim is:

1. A free piston compressor of the class described comprising, axially aligned power, compressor and bounce cylinders, and pistons working therein, a compressed air receiver, means to control the quantity of fuel entering said power

cylinder, means to vary the pressure of air in said bounce cylinders, a member reciprocated by said pistons, and spaced valves operated by said member at each end of its stroke, one valve operating to actuate said fuel control means and the other valve operating said bounce air control means, whereby the stroke of said pistons remains substantially constant.

2. A free piston compressor of the class described comprising axially aligned power, compressor and bounce cylinders, and pistons working therein, means to control the quantity of fuel entering said power cylinder, a vent for said bounce cylinders, a source of high pressure air for said bounce cylinders, fluid operated means to place said bounce cylinders either in communication with said vent to lower the pressure therein or with said high pressure air source to increase the pressure in said cylinders, a member reciprocated by said pistons, and spaced valves operated by said member at each end of its stroke, one valve operating to actuate said fuel control means and the other valve operating said bounce air control means, whereby the stroke of said pistons remains substantially constant.

3. A free piston compressor of the class described comprising axially aligned power, compressor and bounce cylinders, and pistons working therein, a fuel injector, fluid operated means to control said injector to increase or decrease the quantity of fuel entering said power cylinder, a vent for said bounce cylinders, a source of high pressure air for said bounce cylinders, fluid operated means to place said bounce cylinders either in communication with said vent to lower the pressure therein or with said high pressure air source to increase the pressure therein, a member reciprocated by said pistons, and spaced valves operated by said member at each end of its stroke, one valve operating to actuate said injector control means and the other valve operating said bounce air control means, whereby the stroke of said pistons remains substantially constant.

4. A free piston compressor of the class described comprising axially aligned power, compressor and bounce cylinders, and pistons working therein, a compressed air receiver in communication with said compressor cylinders, a check valve controlling the passage of air to said compressed air receiver and preventing return from the receiver to said compressor cylinders, a by-pass to atmosphere on the compressor side of said check valve, means to open said by-pass when the receiver pressure reaches a predetermined level so that the compressor operates thereafter against a substantially atmospheric pressure, means to control the quantity of fuel entering said power cylinder, means to vary the pressure of air in said bounce cylinders, a member reciprocated by said pistons, and spaced valves operated by said member at each end of its stroke, one valve operating to actuate said fuel control means and the other valve operating said bounce air control means, whereby the stroke of said pistons remains substantially constant.

5. A free piston compressor of the class described comprising, axially aligned power, compressor and bounce cylinders, and pistons working therein, a compressed air receiver in communication with said compressor cylinders, a check valve controlling the passage of air to said compressed air receiver and preventing return from the receiver to said compressor cylinders, a by-pass to atmosphere on the compressor side of said check valve, means to open said by-pass

when the receiver pressure reaches a predetermined level so that the compressor operates thereafter against a substantially atmospheric pressure, a fuel injector, fluid operated means to control said injector to increase or decrease the quantity of fuel entering said power cylinder, means to vary the pressure of air in said bounce cylinders, a member reciprocated by said pistons, and spaced valves operated by said member at each end of its stroke, one valve operating to actuate said fuel injector control and the other valve operating said bounce air control means, whereby the stroke of said pistons remains substantially constant.

6. A free piston compressor of the class described comprising, axially aligned power, compressor and bounce cylinders, and pistons working therein, a compressed air receiver in communication with said compressor cylinders, a check valve controlling the passage of air to said compressed air receiver and preventing return from the receiver to said compressor cylinders, a by-pass to atmosphere on the compressor side of said check valve, means to open said by-pass when the receiver pressure reaches a predetermined level so that the compressor operates thereafter against a substantially atmospheric pressure, means to control the quantity of fuel entering said power cylinder, a vent for said bounce cylinders, a source of high pressure air for said bounce cylinders, fluid operated means to place said bounce cylinders either in communication with said vent to lower the pressure therein or with said high pressure air source to increase the pressure in said cylinders, a member reciprocated by said pistons and spaced valves operated by said member at each end of its stroke, one valve operating to actuate said fuel control means and the other valve operating said bounce air control means, whereby the stroke of said pistons remains substantially constant.

7. A free piston compressor of the class described comprising, axially aligned power, compressor and bounce cylinders, and pistons working therein, a compressed air receiver in communication with said compressor cylinders, a check valve controlling the passage of air to said compressed air receiver and preventing return from the receiver to said compressor cylinders, a by-pass to atmosphere on the compressor side of said check valve, means to open said by-pass when the receiver pressure reaches a predetermined lever so that the compressor operates thereafter against a substantially atmospheric pressure, a fuel injector, fluid operated means to control said injector to increase or decrease the quantity of fuel entering said power cylinder, a vent for said bounce cylinders, a source of high pressure air for said bounce cylinders, fluid operated means to place said bounce cylinders either in communication with said vent to lower the pressure therein or with said high pressure air source to increase the pressure therein, a member reciprocated by said pistons and spaced valves operated by said member at each end of its stroke, one valve operating to actuate said injector control means and the other valve operating said bounce air control means, whereby the stroke of said pistons remains substantially constant.

8. A free piston compressor of the class described comprising axially aligned power, and bounce cylinders and pistons working therein, means to control the quantity of fuel entering

said power cylinder, means to vary the pressure of air in said bounce cylinders, each of said pistons comprising a trunk portion between the power and compressor cylinders, a rack connected to said trunk portion of each piston and extending toward the center of the compressor, a synchronizing pinion connecting each of said racks, a mounting shaft for said pinion, a second pinion on said mounting shaft, a rocking lever moved by said second pinion and having abutting members at each end thereof, and spaced valves operated by said abutting members at each end of the stroke of said locking lever, one valve operating to actuate fuel control means and the other valve operating said bounce air control means whereby the stroke of said pistons remains substantially constant.

9. A free piston compressor of the class described comprising axially aligned power, compressor and bounce cylinders and pistons working therein, a fuel injector, fluid operated means to control said injector to increase or decrease the quantity of fuel entering said power cylinder, means to vary the pressure of air in said bounce cylinders, each of said pistons comprising a trunk portion between the power and compressor cylinders, a rack connected to said trunk portion of each piston and extending toward the center of the compressor, a synchronizing pinion connecting each of said racks, a mounting shaft for said pinion, a second pinion on said mounting shaft, a rocking lever moved by said second pinion and having abutting members at each end thereof, and spaced valves operated by said abutting members at each end of the stroke of said locking lever, one valve operating to actuate fuel control means and the other valve operating said bounce air control means whereby the stroke of said pistons remains substantially constant.

10. A free piston compressor of the class described comprising axially aligned power, and bounce cylinders and pistons working therein, means to control the quantity of fuel entering said power cylinder, a vent for said bounce cylinders, a source of high pressure air for said bounce cylinders, each of said pistons comprising a trunk portion between the power and compressor cylinders, a rack connected to said trunk portion of each piston and extending toward the center of the compressor, a synchronizing pinion connecting each of said racks, a mounting shaft for said pinion, a second pinion on said mounting shaft, a rocking lever moved by said second pinion and having abutting members at each end thereof, and spaced valves operated by said abutting members at each end of the stroke of said locking lever, one valve operating to actuate fuel control means and the other valve operating said bounce air control means whereby the stroke of said pistons remains substantially constant.

11. A free piston compressor of the class described comprising axially aligned power, compressor and bounce cylinders, and pistons working therein, a fuel injector, fluid operated means to control said injector to increase or decrease the quantity of fuel entering said power cylinder, a vent for said bounce cylinders, a source of high pressure air for said bounce cylinders, fluid operated means to place said bounce cylinders either in communication with said vent to lower the pressure therein or with said high pressure air source to increase the pressure therein, each of said pistons comprising a trunk portion between the power and compressor cylinders, a rack connected to said trunk portion of each piston

and extending toward the center of the compressor, a synchronizing pinion connecting each of said racks, a mounting shaft for said pinion, a second pinion on said mounting shaft, a rocking lever moved by said second pinion and having abutting members at each end thereof, and spaced valves operated by said abutting members at each end of the stroke of said rocking lever, one valve operating to actuate fuel control means and the other valve operating said bounce air control means whereby the stroke of said pistons remains substantially constant.

12. A free piston compressor of the class described comprising axially aligned power, compressor and bounce cylinders, and pistons working therein, said compressor cylinder being closed at both ends and having intake and exhaust valves at each side of the piston therein, a compressed air receiver in communication with one end of the compressor cylinder, a scavenging receiver header in communication with the opposite end of said compressor cylinder, means to control the quantity of fuel entering said power cylinder, means to vary the pressure of air in

said bounce cylinders, means operated by said pistons when said pistons are at the inner end of their stroke to control the pressure of air in said bounce cylinders, and means operated by said pistons at the outer ends of their stroke to control the quantity of fuel entering said power cylinder whereby said pressure and said fuel quantity are so adjusted that the extent of the stroke of said pistons remains substantially constant.
